US00D524902S

(12) **United States Design Patent** (10) Patent No.: **US D524,902 S**
Masters et al. (45) Date of Patent: ** Jul. 11, 2006

(54) **INSECT TRAP**

(75) Inventors: **Edwin Masters**, Sikeston, MO (US);
Jacqueline Masters, Sikeston, MO (US); **Thomas M. Kollars**, Bealeton, VA (US); **Peggy G. Kollars**, Bealeton, VA (US)

(73) Assignee: **Ticks or Mosquitoes LLC**, Sikeston, MO (US)

(**) Term: **14 Years**

(21) Appl. No.: **29/232,970**

(22) Filed: **Jun. 24, 2005**

(51) **LOC (8) CI. 22-06**

(52) **U.S. CL. D22/122**

(58) **Field of Classification Search** D22/119-125;
43/107, 112-113, 124, 139

See application file for complete search history.

(57) **CLAIM**

The ornamental design for an insect trap, as shown and described.

DESCRIPTION

This application claims priority to U.S. Pat. No. 6,920,716, issued Jul. 26, 2005, which claims the benefit of U.S. Provisional Application Ser. No. 60/467,677, filed May 2, 2003 entitled INSECT TRAP, and U.S. Provisional Application Ser. No. 60/414,936, entitled INSECT TRAP, filed on Sep. 30, 2002, which are herein incorporated by reference in their entireties.

FIG. 1 is a perspective view of an insect trap embodying the invention;

FIG. 2 is a side elevational view thereof;

FIG. 3 is a side elevational view diagonally opposite that of FIG. 2;

FIG. 4 is an elevational view orthogonal to the views of FIGS. 2 and 3;

FIG. 5 is a top plan view thereof; and,

FIG. 6 is a bottom plan view thereof.
